UNITED STATES PATENT OFFICE.

ERIC H. GIBIAN, OF CHICAGO, ILLINOIS, ASSIGNOR TO THE VITROLITE COMPANY, OF PARKERSBURG, WEST VIRGINIA, A CORPORATION OF WEST VIRGINIA.

FRAMELESS COUNTER OR THE LIKE.

Application filed March 24, 1927. Serial No. 177,881.

The present invention relates to counters, soda fountains, or similar structures that are or may be made of slabs of glass-like vitreous material of the kind known under the 5 trade name of Vitrolite; and has for its object to produce a structure of that type that will require no supporting frame that must be set up to receive the slabs.

The vitreous slabs, because of their physical characteristics, must be reinforced in some manner if no supporting framework is to be employed; and a further object of the present invention is to produce a simple and novel compound slab comprising a vitreous facing and a strong, comparatively light and serviceable backing adapted to be fastened to the backing of another slab in building up a structure.

A further object of the present invention 20 is to make a counter, soda fountain, or similar structure from pre-formed slabs that need only be secured together by simple fastening devices at the places where they are to be used.

A further object of the present invention 25 is to construct a counter, soda fountain, or similar structure of preformed slab elements so shaped that structures of various lengths may be obtained by simply adding or subtracting slab sections.

The various features of novelty whereby my invention is characterized will herein-after be pointed out with particularity in the claims; but, for a full understanding of 35 my invention and of its objects and advantages, reference may be had to the following detailed description taken in connection with the accompanying drawings, wherein:

Figure 1 is a perspective view of a counter 40 arranged in accordance with the present invention, showing the rear of the counter; Fig. 2 is a horizontal section, on an enlarged scale, through a corner of the counter; Fig. 3 is a vertical section on a plane extending 45 from front to rear; Fig. 4 is a view similar to Fig. 1, illustrating the front of the counter; Fig. 5 is a vertical section through a top side corner of the counter on a plane at right angles to the plane of Fig. 3; Fig. 6 is a vertical section on a plane extending 50 from front to rear, through the lower portion of a counter, illustrating a modified base 1; and Fig. 7 is a section on an enlarged scale through a fragment of the front wall 55 of the structure.

In carrying out my invention, I make use of metal-sheathed lumber, preferably plywood faced with thin sheet metal glued thereto; the vitreous slabs being cemented to this material which serves as a backing 60 and a reinforcement therefor. This metal sheathed lumber, is strong, comparatively light, and sufficiently flexible to avoid the setting up of objectionable stresses in the vitreous material in the process of manufacturing the compound slabs or under service conditions. The elements forming a compound slab are so shaped and located with respect to each other that no open joints are left in the vitreous facing of an 70 individual slab or any wall composed of several slabs placed end to end.

In the particular arrangement shown in Figs. 1 to 5 of the drawings, the front of the counter, aside from the step, is formed of two slabs or sections, while each end consists of a single section. The top may be of any suitable construction, conveniently a single thick slab of vitreous material, or a plurality of such slabs placed edge to edge. 80

Referring to the drawings, what may be regarded as the left hand front section consists of a panel 1 of metal sheathed lumber comprising preferably a core 2 made out of many piles of wood, say six or seven, and 85 facings 3 of thin sheet metal cemented to the wood. To the front side of the member 1, at about the middle thereof, is cemented a thin slab 4 of vitreous material. Beyond the edges of the member 4 are pieces of lumber 90 5, 6, 7 and 8 cemented to the front face of the member 1 and having approximately the same thickness as the vitreous member 4. The vertical pieces, 5 and 6, project beyond the side edges of the backing member 1. 95 The edges of the vitreous panel 4 are concealed beneath thin narrow slabs of vitreous material 9, 10, 11 and 12 cemented to the pieces of lumber 5, 6, 7 and 8, respectively. The vitreous elements 9 and 10 are considerably wider than the underlying pieces 100 of lumber 5 and 6, so that they project beyond the sides of the latter, on the inner sides overlapping the central vitreous panel 4; while on the outer sides they form with 105 the members 5 and 6 and the backing member 1, a stepped formation into which may be fitted the stepped edge of an adjacent slab.

The adjacent end wall of the counter consists of a backing member 13 similar to the 110

member 1, a central facing panel 14 corresponding to the panel 4, lumber spacing strips 15, 16, 17 and 18 corresponding to the pieces 5, 6, 7 and 8 and narrow panels or finishing strips 19, 20, 21 and 22 overlying the strips of lumber and overlapping the marginal portions of the panel 14.

Since the metal sheathing on the member 13 extends over only the broad faces, a thin sheet of metal 24 is secured over the rear raw edge of this member, and a similar metal sheathing or cap 25 is placed over the rear exposed edge of the piece of lumber 15. Consequently the rear edge of the end wall 15 of the counter, which is exposed, consists either of vitreous material or metal, there being no wood exposed.

In assembling the end wall and the adjacent front section, they are simply set one against the other, the step-like edge formations permitting the two walls to engage each other with the narrow vitreous panel 9 on the front section engaging with the edge of the corresponding panel 19 on the end section, and the front edge of the backing panel 18 engaging with the rear face of the panel 1. In the angle between the two wall sections are placed angle brackets 26 that are bolted or screwed to the backing members 1 and 13; this being the only operation that need be performed in the assembly of the counter to fasten one end wall and the front wall together.

It will be seen that the two ends of the front wall section are similar, so that if a short counter is to be made, a second end wall is simply secured to the right hand end of the front wall section. If a longer counter is required, a plurality of front wall sections are fastened together end to end. In the arrangement shown, the front wall consists of two sections. At the juncture of the two sections is an intermediate wall parallel with the end wall. This intermediate wall may be made of two panels 27 and 28 of material similar to the panels 1 and 13; the panel 28 abutting at its front end against the rear face of the panel 1 and having its outer broad face flush with the side edge of this panel. Suitable angle brackets 29 fasten the members 28 and 1 together. The member 27 lies beside and in contact with the member 28 but abuts against the rear face of the backing member 30 of the second front section. The members 27 and 28 may be fastened together by means of a few small bolts 31 passing through the same.

If the counter is to be provided with a step in front, the main front wall will be made shallower than the end walls, the base panels 22 of the end walls being extended forward far enough to produce the step, and the intermediate partition having portions 32 extending underneath the main front wall to form an intermediate support for the

tread portion 33 of the step or, rather, the metal sheathed supporting panel 34 for the tread. The riser of the step is formed of a slab or a plurality of slabs, consisting of a backing 35 of metal sheathed lumber and a thin panel 36 of vitreous material cemented to the backing. The members 34 and 35 are fastened to the parts 32 and the corresponding elements on the backing members for the end walls by means of angle brackets 37.

Shelves may be provided underneath the counter by securing to the end walls and to the intermediate partition wall angle irons 38; the shelves proper, as indicated at 39, resting on and being bolted to these angle irons.

Each end wall is preferably made in two sections, a main section and a small auxiliary section at the end of the step. In the event that no step is desired, the auxiliary sections of the end walls are left off and the corresponding parts of the intermediate wall are cut off so that the wall stops at the front wall as indicated in the second portion in Fig. 2. Instead of the tread and riser, a base frieze is applied as shown in Fig. 6. In the arrangement shown in this figure, a base section, comprising a backing made up of panels 40 and 41 overlying each other, and a vitreous facing 42 is set directly underneath the main front wall so that the lower part of the front side of the counter, instead of being a step, is simply a frieze of the same height as the base panels on the ends. Of course, if desired, the main front wall may be made deep enough, initially, to extend down to the floor when a counter or the like without a base is desired.

The top 45 of the counter, as shown, consists simply of two large slabs of Vitrolite laid upon the top of the vertical walls; being fastened to the latter by means of angle brackets 46 fastened to the backing members of the vertical walls by screws or the like, and to the vitreous top by screws or studs 47 entered into suitable anchoring sockets 48 laid into the underside of the top.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A counter or the like having a vertical wall formed of metal-sheathed lumber faced with relatively thin slab-like vitreous material cemented thereto.

2. A counter or the like having a vertical wall formed of a plurality of sections arranged edge to edge, each section comprising a back member of metal-sheathed lumber and slab-like vitreous material cemented there-

to, and means fastened to the rear faces of the lumber to secure said sections together.

3. A wall section for a counter or the like comprising a back panel of metal-sheathed lumber, a facing panel of vitreous material cemented to the central portion of the back panel, filling pieces cemented to the back panel around said facing panel, and strips or narrow panels of vitreous material overlapping and cemented to said filling pieces and overlapping the central facing panel at all sides.
4. A wall section for a counter or the like comprising a back panel of metal-sheathed lumber, a facing panel of vitreous material cemented to the front of the back panel, filling pieces surrounding the said facing panel and projecting beyond the edges of the back panel, and narrow panels or strips of vitreous material cemented to said filling pieces and overlapping said central facing panel and projecting beyond the outer edges of the filling pieces at the sides of said section, whereby said section has side edges of step formation.
5. A frameless counter or the like consisting of end walls and a front wall each comprising metal-sheathed backs faced on the outer side with slab-like vitreous material cemented thereto, fastenings between the said backs securing the walls together, and a top resting on said walls.
6. In a counter or the like, a front wall and an end wall engaged with each other at their edges and lying at an angle to each other, each wall comprising a metal-sheathed
- backing and slab-like vitreous material cemented to the outer face of the backing, and angle brackets in the angles between said walls and secured to the backing members to fasten said walls together.
7. A counter or the like having a vertical wall comprising a backing composed of many layers of wood interposed between metal sheets all cemented together, and a relatively thin slab of vitreous material cemented to one of the metal sheets.
8. A frameless counter or the like consisting of a front wall and end and intermediate walls arranged at right angles to said front wall, said front and end walls each comprising metal-sheathed lumber faced on the outer side with slab-like vitreous material cemented thereto, fastening devices arranged in the angles between said front wall and the other walls and secured to the lumber backing, and a top resting on said walls.
9. A frameless counter or the like consisting of a front wall and end and intermediate walls arranged at right angles thereto, said front wall and said end walls comprising metal-sheathed lumber faces on the outer side with slab-like vitreous material cemented thereto, brackets arranged in the angles between said walls, and means for fastening said brackets to the metal-sheathed lumber of the front and end walls, and a top resting on said walls.

In testimony whereof, I sign this specification.

ERIC H. GIBIAN.
